UNITED STATES PATENT OFFICE

Patent to Enos B. Hiatt for a strip of material having a continuous strip with interengaging portions on the ends thereof for temporarily connecting the ends, before the liner is positioned upon a tray or bottom form and within a reinforcing shell, for packing fruit in the manner disclosed in the patents to E. B. Hiatt Nos. 1,573,341 and 1,603,693.

Enos B. Hiatt, Denver, Colo., assignor to The Carpenter-Hiatt Sales Company, Denver, Colo., a corporation of Colorado

Application November 25, 1929 Serial No. 409,493

3 Claims. (Cl. 217—3)

My invention relates to a basket liner of the type described in the patent to E. B. Hiatt, No. 1,593,302, July 20, 1926. The invention consists in making a liner of the general type shown in the said patent, and which is ordinarily of cardboard or similar material, in the form of a discontinuous strip, with interengaging portions on the ends thereof for temporarily connecting the ends, before the liner is positioned upon a tray or bottom form and within a reinforcing shell, for packing fruit in the manner disclosed in the patents to E. B. Hiatt Nos. 1,573,341 and 1,603,693.

The present liners are generally similar to that disclosed in an application of Frederick A. Read, Jr., Ser. No. 362,179, filed May 11th, 1929, with improvements consisting in providing the ends of the strip with more positively interlocking connecting formations of different types, as referred to in detail hereafter, and in providing for adjustment, or adjustable action of the connecting devices to accommodate the liner to baskets of varying degrees of taper.

The interlocking or connecting formations are provided near the ends of the liner strip, and in use as the strip is bent or set up in approximately conical form, these formations are interengaged to maintain the strip in the stated form during packing of fruit in accordance with the well-known Hiatt method as set forth in the above mentioned patents. After the liner, supported by a shell and inverted upon a packing lid, has been filled with fruit, the external support or shell is removed and thereupon the interlocking formations prevent separation of the ends of the liner so that it properly supports the column of fruit. It will of course be understood that for the purposes of the Hiatt process, the material of the liner is such that it possesses sufficient inherent strength to hold the column of fruit without any other support after the packing shell has been removed. An inverted basket is now placed over the liner with its contained column of fruit and the whole assembly is inverted with a jolt which is sufficient to make the liner yield in one or more places throughout the body thereof, or cause the interlocking formations to be partly or completely ruptured, or to slip relatively, permitting the liner to adjust itself against the basket wall, and also to adjust itself to baskets of varying diameters, and thus allow the proper settling and compacting of the fruit in the basket.

The characteristics and advantages of the invention are further sufficiently explained in connection with the following detailed description

of the accompanying drawing, which shows certain representative embodiments. After considering these examples, skilled persons will understand that many variations may be made without departing from the principles disclosed, and I contemplate the employment of any structures that are properly within the scope of the appended claims.

In the drawing:

Fig. 1 is a view of one of the liners embodying the invention, in flat or strip form.

Fig. 2 shows the two ends of the liner being brought together preparatory to interlocking them.

Fig. 3 shows the same connected.

Fig. 4 shows the two ends of a liner, having modified interlocking formations, being brought together for fastening.

Fig. 5 shows the same connected.

The liner 20 consists of a strip of suitable sheet material such as cardboard of moderate strength and stiffness, but of such texture or character as to readily yield and conform to the shape of a fruit basket or vegetable crate, but at the same time strong enough to properly support a column of fruit packed therein, as and for the purposes explained in the above-mentioned Hiatt patents.

The edges 21 of the strip are arcuate to enable it to assume a substantially conical form when set up for use. Usually a plurality of ventilating holes 22 are punched in the strip, and transverse score lines 23 may also be provided if desired to facilitate folding for shipment of the strips in bundles or to facilitate bending the strip to conical form.

The ends of the strip have cut therein complementary hook formations 30 directed respectively upward and downward from a central point or axis of the strip. When the strip is set up these hooked formations are engaged in a manner which is fully explained in Fig. 3, thus providing a positive interlocking connection of the strip ends. When joined in the basket, these hook formations may stretch or rupture more or less, with or without accompanying stretching or partial rupture of the strip at various points, to allow for the proper compacting of the fruit in the basket.

In Fig. 4, the ends of the strip are angularly notched at 50 and vertically slit at 51 providing interlocking hooks or tongues 52 with slant edges 53. These hooks are interlocked by an inward and lateral relative movement of the strip ends as they are brought together, as shown in Fig. 5.

It will be understood from the forms specifi-
